UNITED STATES PATENT OFFICE.

LEWIS P. HALLADAY, OF MARION, INDIANA.

DESIGN FOR A POISE FOR SCALES.

SPECIFICATION forming part of Design No. 31,506, dated September 12, 1899.

Application filed May 11, 1899. Serial No. 716,445. Term of patent 7 years.

To all whom it may concern:

Be it known that I, LEWIS P. HALLADAY, a citizen of the United States, residing at Marion, in the county of Grant and State of Indiana, have invented and produced a certain new and original Design for a Poise for Scales, of which the following is a specification.

My invention relates to a new and original design for a poise for scales.

My invention is illustrated in the accompanying drawings, wherein—

Figure 1 is a front view of a poise embodying my design. Fig. 2 is a side view of the same.

Like letters refer to like parts throughout both figures.

The poise herein shown is particularly adapted for what is termed an "even-balance" scale. In this form of scale the poise as it moves along the scale-beam upon which it is

suspended is sometimes on one side of the center of oscillation and sometimes on the other side. My design comprises a circular weight A, having one of its end faces cut away, as shown at B, for the scale-beam. The upper edge of this cut-away portion is substantially on a line with the center of the poise and is provided with the indicating-point A'.

The essential feature of my design is the circular poise A, having one of its end faces cut away, the upper edge of the cut-away portion being substantially on a line with the center of the poise.

I claim—

The design for a poise for scales as herein shown and described.

LEWIS P. HALLADAY.
